UNITED STATES PATENT OFFICE.

GEORGE THOMAS, OF ROYERSFORD, PENNSYLVANIA.

FURNACE.

No. 807,976.

Specification of Letters Patent.

Patented Dec. 19, 1905.

Application filed May 17, 1904. Serial No. 208,438.

To all whom it may concern:

Be it known that I, GEORGE THOMAS, a citizen of the United States, residing at Royersford, in the county of Montgomery and State 5 of Pennsylvania, have invented new and useful Improvements in Furnaces, of which the following is a specification.

My invention relates to improvements in furnaces.

10 Said invention has for its object to promote combustion by the aid of superheated steam or air, or both, the same producing a uniform and steady supply of oxygen over the fire-bed or products of combustion, thus 15 providing for the effective combustion of all smoke and gases or other freed products, consequently effecting a saving of fuel and increasing the heating action of the furnace.

Said invention consists of detailed structural features substantially as hereinafter 20 more fully disclosed, and particularly pointed out by the claim.

In the accompanying drawings, illustrating the preferred embodiment of my invention, Figure 1 is a broken perspective view 25 thereof. Fig. 2 is a horizontal section produced in the plane of the lower superheated steam and air conduits or passages of one half of the furnace and a like section produced in the plane of the upper superheated 30 steam and air conduits or passages of the other half of said furnace. Fig. 3 is a view of a half- or one section of one of the bricks used in constructing said conduits or passages. Fig. 4 is a view showing such a brick 35 with the sections or halves thereof assembled.

In the carrying out of my invention I construct the furnace 1 generally in the ordinary way, providing, however, the combustion-chamber 2 with lateral and rear wall conduits or passages 3 and 4, respectively, of the character or construction as hereinafter disclosed for feeding or delivering, as above 40 noted, superheated steam or air, or both, into said chamber to aid or promote combustion. Each conduit or passage, whose inlet end or intake 3^a is preferably at the front end of the furnace, traverses one side of the 45 combustion-chamber and about one-half of the rear wall, where it extends upward, as at 3^b, and returning parallel with itself terminates a short distance from the forward end of the furnace and opens through said lateral 50 wall of the combustion-chamber, as at 3^c, for the discharge or delivering of the super-

heated steam and air into said chamber. It is noted that the purpose of returning said conduit and terminating the discharge end thereof in a plane higher than its other portion and intake end is to provide for a more satisfactory circulation or passage therethrough than would otherwise be the case of the air and its effective delivery upon the fire-bed. Said conduits are constituted or 60 constructed of fire bricks or blocks 3^x, each being produced in halves and hollow, with the halves brought together to form the conduits, said blocks or bricks being of the usual or angular exterior or outline, as shown, to 65 form the inner surfaces of the lateral and rear walls of the combustion-chamber.

Steam-delivery pipes 4, one for each conduit or passage and connected with a boiler or steam - generator, have their discharge 70 ends entering the intake ends of said conduits and extending a suitable distance within the same for suitably feeding or supplying steam thereto, which will by its passage therethrough be superheated and be thus 75 discharged, together with air simultaneously entering and sucked into said conduits, into the combustion-chamber upon the fire-bed or products of combustion, thereby providing for effecting the combustion of the gases, 80 smoke, and other freed products, thus increasing the heating action of the furnace and 85 economizing fuel. The aforesaid arrangement of conduits or passages effects more than would otherwise be the case increased 90 feeding action of the superheated steam and air, thus securing a more thorough combustion of the products freed from the fuel in combustion. Also by providing for the continuous feeding to the fire-bed of said steam 95 and air and the return passages thereof during such feeding action, subjecting the steam and air to a reheating action, the latter are delivered in their most effective form upon the fire-bed.

It will be noted that this invention embraces improvements in furnaces which are especially applicable for use in connection with boilers, as is obvious and as will be fully appreciated from the foregoing.

It is understood that latitude is allowed as to details herein, as they may be changed as circumstances suggest without departing from the spirit of my invention and the latter still be protected.

I claim—

A furnace of the character described, whose

combustion-chamber has its walls comprising courses of bricks, each formed in hollow joined-together sections forming conduits or passages, means for feeding the air and superheated steam into said conduits, and said conduits delivering into the combustion-chamber, and each of the thus formed conduits having its intake end at the front or one end of the combustion-chamber and itself traversing one side and about one-half the rear wall thereof and extending upward in

the latter wall and returning upon itself, and having its discharge end arranged above its intake end delivering near the same end of said chamber and thereinto.

In testimony whereof I have signed my name to this specification in the presence of two subscribing witnesses.

GEORGE THOMAS.
